UNITED STATES PATENT OFFICE.

JOSEPH HREN, OF KINGSTON, NEW YORK, AND CARL EISENLOHR, OF NEWARK, NEW JERSEY.

ANTIFRICTION BEARING.

Application filed May 25, 1925. Serial No. 32,668.

This invention relates to a presser bearing for machines of the class shown and described in a Patent No. 1,560,162, granted to us November 3, 1925, the object thereof being to provide an anti-friction bearing to eliminate undue wear, a feature being the provision of co-acting parts one being mounted in floating or free relation with respect to the others to reduce to a minimum frictional retarding action of the parts, especially when maximum pressure is exerted on the bed plate when sealing box blanks by a wet adhesive.

Broadly, the invention aims to eliminate friction by supplying a rolling contact of the parts and also to do away with springs in any form.

The application of the invention as herein shown depicts the pressure head arranged at an angle, but of course it may be horizontal, or only slightly inclined, and its operation will be equally effective.

We clearly illustrate our invention in the accompanying drawings, which form a part of this specification, and in which drawings similar reference characters are employed to indicate like parts, and in which:—

Figs. 1, 2, and 3, are side elevations of a presser head and its co-acting table, showing our improved bearing in position, the parts being in progressive changed operative positions in the progressive views.

Fig. 4 is a cross section on the line 4—4 of Fig. 2.

Referring to the drawings, we show at 10, one of a pair of presser heads mounted in the usual guides (not shown) and below the head is a yieldingly mounted presser table 11, of any desired form, and in the operation of the machine, sheets 12, of cardboard are down onto the table in overlapped relation, with wet adhesive covering the overlapped faces so that the presser head seals them one to the other when it is forced down by a cam 13, on a power shaft 14.

The cam rotates in a circular opening 15, in a presser block 16, having a base 17, to fit between the lugs 18, of an upper presser pad 19, having side grooves 20, to receive the

tops of plates 21, which confine the parts in place against lateral movement.

A lower presser pad 22, is seated in the head 10, and between the pads is a cage 23, having openings 24, and an opening or loop 24^a and in the openings 24, are rollers 25, slightly larger in diameter than the thickness of said cage, while opening or loop 24^a, receives a pin or nose 26, carried on upper pad 19, which acts to draw the cage up the incline from the position shown in Fig. 3 to that of Fig. 1, on the forward and over swing of the cam and on the downward and backward swing of the said cam the cage follows said pin by the action of gravity, until the pressing action begins, when said pin will travel in the opening or loop 24^a, twice as fast as the cage moves over the lower pad, so that the parts will be in the position shown in Fig. 3 at the end of the back stroke.

The presser head is provided with an opening 27, of a size to accommodate the reciprocal movements of the bearing parts.

It will be understood that modifications of our invention may be resorted to, in the adaptation thereof to various conditions of use, as properly fall within the scope of the invention claimed.

What we claim as new and desire to secure by Letters Patent is:—

1. An anti-friction bearing comprising an upper moving pad and a lower fixed pad, a cage movable on the lower pad and having rollers therein and a loop at the end thereof, said upper pad being provided with end lugs to engage a presser block and a pin adapted to enter the loop of the cage to draw it forward after the pressing operation.

2. In combination with a presser head of a box blank making machine, a presser block, an upper pad having lugs to engage the block, and a downwardly directed pin, a roller receiving cage having a loop at one end to receive the pin to draw the cage forwardly and upwardly on the forward inoperative stroke of the presser block, and a lower fixed pad to support the cage and its rollers.

3. An anti-friction bearing adapted to op-

erate at an angle to the horizontal in combination with a presser head having an opening in which parts of the bearing reciprocate and which comprise a lower pad imbedded in the head, a roller carrying cage having an end loop, an upper pad having end lugs to engage a presser block and a pin to enter and engage the loop to draw the cage for-

ward and upward on the forward inoperative stroke of the presser block prior to the beginning of the downward and backward operative pressing stroke thereof. ¹⁰

In testimony whereof we have affixed our signatures.

CARL EISENLOHR.
JOSEPH HREN.
